UNITED STATES PATENT OFFICE.

JOSEPH LITTLE, OF OELWEIN, IOWA.

LOCOMOTIVE-WHEEL-FLANGE OILER.

1,102,524.

Specification of Letters Patent. Patented July 7, 1914.

Application filed July 25, 1910. Serial No. 573,740.

To all whom it may concern:

Be it known that I, JOSEPH LITTLE, a citizen of the United States, residing at Oelwein, in the county of Fayette and State of Iowa, have invented a certain new and useful Locomotive-Wheel-Flange Oiler, of which the following is a specification.

The object of my invention is to provide an oiling device of simple, durable and inexpensive construction for the purpose of oiling the flanges of locomotive wheels to prevent wear upon them in passing around curved tracks.

More specifically it is my object to provide a device of this kind in which the oil reservoir and supply pipe leading to the wheel flange may be warmed during cold weather by means of exhaust steam from the locomotive and also the oil may be forcibly carried to the locomotive wheel flange by steam pressure so that the oil is kept in suitable condition for flowing and at the same time its passage may be accelerated by the passage of steam through the oil pipe.

My invention consists in certain details, in the construction, arrangement and combination of the various parts of the device, whereby the objects contemplated are attained, as hereinafter more fully set forth, pointed out in my claim and illustrated in the accompanying drawings, in which:

Figure 1 shows a side elevation of two locomotive wheels having my improved oiling device applied thereto. Fig. 2 shows an enlarged, detail, sectional view of my improved oiling device and a portion of a locomotive wheel adjacent thereto. Fig. 3 shows an enlarged, detail, sectional view of my improved oiling device taken on a line 40 at right angles to that on which Fig. 2 is taken, and Fig. 4 shows an enlarged, detail, sectional view of the discharge end of the oiling device.

Referring to the accompanying drawings, I have used the reference numeral 10 to indicate a locomotive wheel having a tread portion 11 and a flange 13, the face of the flange adjacent to the tread portion being slightly inclined at 14 as clearly shown in Fig. 2. This is the ordinary shape of locomotive wheel flanges.

My improved oiling device comprises a cylindrical oil receptacle 15 having a screw cap 16 at its top. Surrounding the oil receptacle 15 is a steam jacket 17 having a steam inlet pipe 18 and also having a dis-

charge extension 19 at its lower end for oil and steam. Arranged at the bottom of the oil receptacle is a valve casing provided with a valve 20 of ordinary construction so arranged as to regulate the flow of oil from the oil chamber to the discharge extension 19. A passage way 21 is also provided in the bottom of the jacket 17 so that the interior of the jacket communicates with the said discharge extension below the valve. Screwed into the discharge extension 19 is a discharge pipe 22 and this pipe is extended first straight downwardly and then laterally and downwardly in a direction toward a wheel flange as shown in Fig. 2. Slidably mounted on the lower end of the discharge pipe 22 is a collar 23 to which is fitted a cylindrical flexible oiling member 24 which may, if desired, be made of a piece of rubber hose or similar material. The lower end of this oiling member is tapered at 25 to fit against the surface 14 of a wheel flange. Mounted on the lower end of the discharge pipe 22 is a nut 26 arranged with in the oiling member 24 and which limits the downward movement of said oiling member relative to the discharge pipe. The said pipe however is free to move upwardly with the collar 23 but is ordinarily held by gravity and by the shaking of the pipe 22 to position where the beveled lower end thereof will rest against a wheel flange. The entire oiling device may be supported in position by means of a screw threaded rod 28 seated in a suitable socket 29 formed in one side of the steam jacket as shown in Fig. 3.

For supplying steam to the steam jacket I attach a steam pipe 30 to the pipe 18 leading to the jacket and this steam pipe 30 is designed to be connected to some suitable source of steam supplied from the locomotive, preferably the exhaust from the locomotive air pump.

In practical use I first fill the oil receptacle with oil and then place the screw cap thereon; then the valve 20 may be opened to the desired extent and steam may be discharged into the jacket in any desired manner. The steam will have an outlet through the discharge pipe 22 and therefore will warm not only the entire outer surface of the oil receptacle but also the valve casing and the discharge pipe, and furthermore the steam is permitted to flow through the discharge pipe to thereby create more or less

of a vacuum below the valve to draw oil through the valve and to discharge it into the oiling member 24. In this manner I prevent all possibility of dust accumulating around the discharge pipe or in the valve in such a manner as to prevent the successful operation of the oiler. The flow of oil may be regulated in two ways either by the amount of steam used or by the valve 20 or both.

By having the oiling member 24 slidingly mounted upon the discharge pipe 22 it will always stand in frictional engagement with the wheel flange, and furthermore the parts are so arranged that a new oiling member 24 may be readily and easily substituted when one is worn out.

I claim as my invention:
An improved locomotive wheel flange

oiler, comprising an oil receptacle, a discharge pipe communicating with the oil receptacle and extended downwardly and laterally, a valve for controlling the passageway from the receptacle to the discharge pipe, a sleeve fitted to and slidingly mounted on the lower end of the discharge pipe, a cylindrical flexible oiling member fixed to said sleeve, and a nut detachably mounted on the lower end of the discharge pipe contained within said cylindrical oiling member to thereby provide for detaching the cylindrical oiling member from the discharge pipe.

Des Moines, Iowa, July 13, 1910.
JOSEPH LITTLE.
